(57) **CLAIM**

The ornamental design for a sanitary article, as shown and described.

DESCRIPTION

FIG. 1 is a top plan view of a sanitary article showing our new design.

FIG. 2 is a bottom plan view thereof.

FIG. 3 is a front elevational view thereof.

FIG. 4 is a rear elevational view thereof.

FIG. 5 is a left side elevational view thereof; and,

FIG. 6 is a right side elevational view thereof.

The broken lines shown in FIG. 2 illustrate portions of the sanitary article that form no part of the claimed design.

1 Claim, 4 Drawing Sheets

FIG. 1

FIG. 2

FIG. 3

FIG. 4

FIG. 5

FIG. 6
